S. CHAZEN ET AL

HOG SHACKLER

Filed May 14, 1923

FIG. 3.

Inventors

S. Chazen
C. J. Madsen

By Milton E. Lowry.

UNITED STATES PATENT OFFICE.

SAMUEL CHAZEN AND CARL J. MADSEN, OF MASON CITY, IOWA.

HOG SHACKLER.

Application filed May 14, 1923. Serial No. 638,799.

To all whom it may concern:

Be it known that we, (1) SAMUEL CHAZEN and (2) CARL J. MADSEN, (1) a citizen of Russia, having declared his intention to become a citizen of the United States of America, and (2) a citizen of the United States of America, residing at Mason City, in the county of Cerro Gordo and State of Iowa, have invented certain new and useful Improvements in Hog Shacklers, of which the following is a specification.

This invention relates to new and useful improvements in shackling devices employed for handling animals, such as hogs and sheep, in packing plants or the like.

It is the present custom of packing houses to employ devices which are adapted for securely grasping the leg of an animal to enable the same to be suspended upon a trolley track in a position suitable for allowing preliminary steps, such as stabbing, bleeding, scalding, scraping, and skinning, to be performed by the packers. After the animal has passed through the various departments wherein the above mentioned, and other desired, operations are performed, the body is removed from the suspension means for the purpose of allowing further preparation of the same.

It is the primary object of this invention to provide a shackling device which is suitable for securely grasping the leg of an animal for the purpose of suspending its body on a track or the like.

A further object of the invention is to provide a device of the above mentioned character which is constructed so as to cause the gripping elements to exert a grasping force coincident with the weight of the object being suspended.

A further object of the invention is to provide a device which will automatically release the object being supported upon reaching a predetermined point in the conveyor track.

A further object of the invention is to provide a locking element for the device noted above which will prevent accidental releasing of the object prior to its reaching the predetermined point referred to.

A still further object of the invention is

to provide a device of the above mentioned character which is compact and light in construction and one that may be easily disassembled for the purpose of allowing the same to be cleaned or for replacing worn out or broken parts.

Other objects and advantages of the invention will be apparent during the course of the following description.

In the accompanying drawing forming a part of the specification and in which like numerals are employed to designate like parts throughout the same,

Figure 1 is a side elevational view, partly broken away, of the shackle device embodying this invention.

Figure 2 is a fragmentary partly sectionally and partly elevational view of the lower end of the shackle device showing principally the grappling members and the elements directly associated therewith, and

Figure 3 is a fragmentary view partly in elevation and partly in longitudinal section of a locking means employed for preventing the accidental releasing of the grappling elements.

In the drawing, wherein for the purpose of illustration is shown a preferred embodiment of this invention, the numeral 5 designates a substantially tubular body portion having formed at its lower end an enlarged shell portion 6 that is provided with openings 7 at the extreme outer end of the same, and the said body portion 5 being further provided with a transverse partition 8 having an aperture 9 positioned axially therein. Secured to the upper end of the tubular body portion 5 is a reducing coupler 10 having secured to its reduced portion a second tubular member 11 which is substantially closed at its upper end by means of a cap element 12 having an axially arranged aperture 13 formed therein.

Slidably positioned in the tubular body portion 5 and guided by the transverse partition 8 is a rod member 14 having threadedly connected with its lower end a block 15 which is provided with a set of spaced transversely extending ears 16 at its free end which are adapted for receiving the inner ends of the grappling elements 17.

pivotedly secured thereto by means of the pins 18. Positioned between the transverse partition 8 and the block 15 is a spiral spring 19 which tends to force downwardly on the said block for the purpose of moving the said grappling elements 17 outwardly of the shell member 6 thereby causing the elements to assume their relative positions as shown in Fig. 1, there being 10 provided a transverse wall portion 6^a formed between the openings 7 in the shell portion 6 which is provided with diverging faces 6^b against which the adjacent edges of the grappling elements 17 bear for the 15 purpose of causing them to assume the position referred to above and shown in Fig. 1. Secured to the upper end of the rod 14, as by the pair of locking nuts 20 is a shackle member 21 having a roller element 22 secured thereto, as best shown in Fig. 1.

Slidably associated with the second tubular member 11 and adapted for projecting outwardly thereof through the aperture 13 formed in the cap 12 is an upper rod member 23 having a desired portion of its length serrated or grooved as at 24 for a purpose to be described at a later point. Referring particularly to Fig. 1 it will be seen that the upper end of the rod 23 is slightly reduced 25 at 25 for swivel connection with a collar member 26 having an eye portion 27 formed therein that is adapted for connection with a hook element 28 by means of the link 29, the said collar 26 being further provided 30 with a laterally extending tubular portion 30 which is adapted for slidably receiving the shank of the hook element 31 which is constructed from square stock having a circular reduced portion formed at its lower 35 end that is threaded for the purpose of receiving the guiding element 32 secured thereto by means of the nut 33, the said guiding element having an enlarged opening 34 formed therein that is adapted for slidably 40 engaging the second tubular member 11.

For the purpose of operatively connecting the upper rod 23 and lower rod 14, there is provided a link chain 35, shown best in Fig. 1, which is connected to the lower end of 50 the upper rod 23, as at 36, and extends downwardly to be inserted through the shackle 21 and then upwardly to slightly project through an opening formed in the side wall of the reducing coupler head, the 55 projecting end being provided with a pin 37 which prevents the drawing of the said chain entirely within the reducer 10 and tubular body portion 5.

Referring particularly to Fig. 3, it will 60 be seen that the upper tubular portion 11 is provided in proximity to the cap member 12 with diametrically opposed longitudinally extending slots 38 and 39 which are of different lengths, the upper ends of the said slots 65 being transversely alined while the lower

end of the longer slot 39 will be positioned somewhat below the lower end of the smaller slot 38. Positioned within the upper tubular portion 11 and slidably engaging the serrated portion 24 of the under rod 23 is a disk member 40 having diametrically opposed ears 41 that project outwardly through the said slots 38 and 39. There is further provided a coil spring 42 having its upper end bearing against the inner face of the cap element 12 while its lower end bears against the disk 40. As shown in this figure, the spring 42 bearing against this locking element will cause the same to move away from the cap 12 with the result that the ear 41 projecting through the smaller slot 38 will bear against the inner end of the same which will cause the said locking element to cant or resume a position on an angle to the longitudinal axis of the upper rod 23 thereby causing the said locking member to engage the serrated surface 24 for preventing movement of the said rod 23 in a direction towards the grappling elements 17.

The operation of the device is as follows: Briefly stated, the grappling elements 17 are to be positioned as shown in Fig. 2 in locked engagement with an animal's leg after which the shackling device and the animal are to be suspended upon a trolley track by means of the hook 28. The animal, in this manner, is conveyed along the track while the various preliminary operations are performed thereupon until the body arrives at a predetermined point in the trolley where there is located a second trolley track that engages the second hook element 31. After the hook element 31 is properly engaging the second track, the first track terminates with the result that the weight of the body shifts from the hook 28 to the hook 31 thereupon the locking disk 40 is moved to an inoperative position due to the upward movement of the guiding element 32 which is caused by the transferring of the weight of the body as just described. It will therefore be seen that all upward pull is removed from the lower rod 14 with the result that the spiral spring 19 will cause the block 15 to move downwardly or in a direction towards the shell 6 thereby causing the grappling elements 17 to assume the position as shown in Fig. 1 with the result that the body is released and allowed to separate from the shackling device. The shackling device is then returned in any desired manner to the starting point of the first trolley track where it may be again employed for conveying an animal over the same.

Describing the operation more in detail, the body portion 11 between 32 and 10 is preferably grasped in one hand of the operator while his other hand is positioned in engagement with the hook 28 after which the grapple carrying end of the shackling

device is associated in proximity to the animal's leg whereupon an upward or outward pull is exerted upon the hook 28 which will cause the upper rod 23 to move outwardly 6 through the aperture 13 formed in the cap 12. This outward movement of the rod 23 will naturally draw the upper end of the link chain 35 after the same with the result that the said chain will pass beneath the 10 roller member 22 thereby causing an inward movement of the block 15 against the tension of the spiral spring 19. This inward movement of the block 15 will cause the grappling elements 17 to be partly drawn 15 within the shell member 6 with the result that the outer edges of the apertures or openings 7 will cause the said grappling elements to assume the position as shown in Fig. 2 thereby securely grasping the animal's leg. It is to be understood that upward movement of the rod 23 will be allowed, notwithstanding the position of the locking disk 40, as shown in Fig. 3, for this locking disk will also move upwardly with 20 the said rod until the ears 41 are positioned in engagement with the upper transversely alined ends of the slots 38 and 39 whereupon the said disk will be moved into an inoperative 25 position and will not engage the serrated portion 24 of the said rod. However, after the upward movement of the rod 23 has stopped, the spiral spring 42 will cause the locking disk 40 to again assume the position as shown in Fig. 3 with the result that 30 downward or inward movement of the upper rod 23 is prevented. At this time, it will be seen that the grappling elements 17 will be prevented from changing to the position as shown in Fig. 1 on account of this locking element 40. The hook 28 is then placed in proper engagement with the trolley track, not shown. After the body and the shackling device have been conveyed over the trolley track through the various 35 departments wherein the desired work is performed, a second trolley track is encountered which operatively engages the second hook element 31 with the result that the shackling device is transferred from the first trolley track to the second mentioned track. The shifting of the weight to the hook 31 will cause the hook shank to move upwardly 40 through the tubular extension 30 and the guiding element to slide upwardly upon the upper tubular member 11 with the result that the locking disk 40 will be moved upwardly against the tension of the spring 42 until the ears 41 engage the transverse alined ends of the slots 38 and 39. This movement 45 of the lock disk 40 will release the rod 23 and allow the tensioned spring 19 to force downwardly upon the block 15 with the result that the shackling elements are allowed to assume the positions as shown in Fig. 1, thereby releasing their hold upon the ani-

mal. As stated above, the shackling device is then returned in any desired manner to the starting of the first track where it may be again employed to convey a body over the same.

It is to be understood that the form of this invention herewith shown and described is to be taken as a preferred example of the same, and that various changes in the shape, size, and arrangement of parts may be resorted to without departing from the spirit of the invention or the scope of the subjoined claims.

Having thus described the invention, I claim:—

1. In a device of the class described, a body portion, a tubular member secured thereto, an element slidably positioned in said body portion, grappling hooks pivotally secured to said element, an element slidably positioned in said tubular member, a supporting hook secured to the second mentioned element, and flexible means operatively connecting said element for moving said grappling hooks into their operative positions when the second mentioned element is moved outwardly of said tubular member.

2. In a device of the class described, a body portion, a tubular member secured thereto, an element slidably positioned in said body portion, grappling hooks pivotally secured to said element, a second element slidably positioned in said tubular member, a supporting hook secured to the second mentioned element, flexible means operatively connecting said element for moving said grappling hooks into their operative positions when a pulling force is exerted upon said supporting hook to move the second mentioned element outwardly of said tubular member, and locking means for preventing the inward movement of the second mentioned element after the grappling hooks have been moved to their operative position.

3. In a device of the class described, a body portion, a tubular member secured thereto, an element slidably positioned in said body portion, grappling hooks pivotally secured to said element, a second element slidably positioned in said tubular member, a supporting hook secured to the second mentioned element, flexible means operatively connecting said elements for moving said grappling hooks into their operative positions when a pulling force is exerted upon said supporting hook to move the second mentioned element outwardly of said tubular member, locking means for preventing the inward movement of the second mentioned element after the grappling hooks have been moved to their operative positions, and means for releasing said locking means when it is desired to allow the grap-

pling hooks to assume their inoperative position.

4. In a device of the class described, a body portion, a tubular member secured thereto, a rod slidably associated with the body portion, grappling elements pivotally carried by said rod, a second rod slidably associated with the tubular member, a hook element carried by the second mentioned rod, and flexible means operatively connecting said rods for moving said grappling elements into their operative positions when force is exerted upon said hooks to move the second mentioned rod longitudinally of the tubular member.

5. In a device of the class described, a body portion, a tubular member secured thereto, a rod longitudinally movable in said body portion, a block secured to the outer end of said rod, grappling elements pivotally carried by said block, a second rod longitudinally movable in said tubular member and projecting from its outer end, flexible means operatively connecting the inner ends of said rods for moving said grappling elements into their operative positions when the second mentioned rod is moved outwardly of the tubular member, and means for returning said grappling elements to their inoperative position when the second mentioned rod is moved inwardly of the tubular member.

6. In a device of the class described, a body portion, a tubular member, a coupler connecting said body portion and tubular member, an element slidably associated with said body portion, grappling hooks pivotally carried by one end of said element, a roller member associated with the other end of said element, a rod slidably associated with the tubular member and projecting from its free end, and flexible means secured to said rod slidably engaging said roller member and anchored to said coupler for causing said grappling hooks to assume their operative positions when said rod is moved outwardly of said tubular member.

7. In a device of the class described, a body portion, a coupler secured to one end of said body portion, a shell portion having spaced openings carried by the opposite end of said body portion, an element slidably positioned in said body portion, grappling hooks pivotally associated with said element and projecting through said spaced openings, and flexible means anchored to said coupler at one end operatively connected to said rod and projecting from said coupler whereby outward movement of said flexible means thru said coupler will cause the grappling hooks to assume their operative positions.

8. In a device of the class described, a body portion, a coupler secured to one end of said body portion, a shell portion having

spaced openings carried by the opposite end of said body portion, an element slidably positioned in said body portion, grappling hooks pivotally associated with said elements and projecting through said spaced opening, flexible means anchored to said coupler at one end operatively connected to said rod projecting from said coupler at its opposite end whereby outward movement of said flexible means from said coupler end will cause said grappling hooks to assume their operative positions, and means associated with said slidible element for causing said hooks to assume their inoperative positions when said flexible means is allowed to move inwardly of said coupler.

9. In a device of the class described, a body portion, a tubular member secured thereto, an element slidably positioned in said body portion, grappling hooks pivotally carried by said element, a rod slidably positioned in said tubular member, a supporting hook carried by said rod, flexible means operatively connecting said slidible element and rod for causing said grappling hooks to assume their operative positions when said rod is moved outwardly of said tubular member, and means carried by said tubular member for preventing inward movement of said rod after said hooks have been moved to their operative positions.

10. In a device of the class described, a body portion, a tubular member secured thereto, an element slidably positioned in said body portion, grappling hooks pivotally carried by said element, a rod having a portion of its length serrated slidably positioned in said tubular member, a supporting hook carried by said rod, flexible means operatively connecting said slidible element and rod for causing said grappling hooks to assume their operative positions when said rod is moved outwardly of said tubular member, a locking element loosely carried by said tubular member, and means associated with said tubular member for causing said locking element to engage the serrated portion of said rod for preventing inward movement of the latter after said hooks have been moved to their operative positions.

11. In a device of the class described, a body portion, a tubular member secured thereto, an element slidably positioned in said body portion, grappling hooks pivotally carried by said element, a rod having a portion of its length serrated slidably positioned in said tubular member, a supporting hook carried by said rod, flexible means operatively connecting said slidible element and rod for causing said grappling hooks to assume their operative positions when said rod is moved outwardly of said tubular member, a locking element loosely carried by said tubular member, means associated

with said tubular member for causing said locking element to engage the serrated portion of said rod for preventing inward movement of the latter after said hooks have been moved to their operative positions, and a second supporting hook slidably associated with said tubular member for moving said

locking element into its inoperative position when pulling force is exerted upon the second supporting hook.

In testimony whereof we affix our signatures.

SAMUEL CHAZEN,
CARL J. MADSEN.
